Primary Examiner — Carla J Wright(57) **CLAIM**

The ornamental design for wallet for card, cash and cellphone, as shown and described.

DESCRIPTION

FIG. 1 is a front elevation view of a wallet for card, cash, and cellphone showing my new design;

FIG. 2 is a rear elevation view thereof;

FIG. 3 is a left-side elevation view thereof;

FIG. 4 is a right-side elevation view thereof;

FIG. 5 is a top plan view thereof;

FIG. 6 is a bottom view thereof;

FIG. 7 is a front perspective view thereof showing the case in a folded configuration;

FIG. 8 is a perspective view of the interior thereof showing the case in an unfolded configuration;

FIG. 9 is an elevation view of the exterior thereof showing the case in an unfolded configuration; and,

FIG. 10 is an elevation view of the interior thereof showing the case in an unfolded configuration and showing the rear of the cell phone holder which is separated from the wallet for clarity of disclosure.

The broken lines in the drawing figures depict stitching, which is part of the claimed design.
